MACHINE FOR PRODUCING TUFTED FABRICS

Walter Y. Robb, Whitinsville, and Harold L. Blanchard, Millbury, Mass., assignors to Crompton & Knowles Loom Works, Worcester, Mass., a corporation of Massachusetts

Application March 16, 1955, Serial No. 494,778

37 Claims. (Cl. 112—79)

This invention relates to improvements in machines for forming tufted fabrics such as are suitable more particularly though not necessarily for floor coverings and it is the general object of the invention to provide such a machine, and also a method of operation, capable of producing a fabric having a fancy pattern.

Machines have been developed heretofore for the production of tufted fabrics by a punching operation, but such machines are not ordinarily adapted to the manufacture of tufted fabrics having a fancy pattern. It is an important object of the present invention to provide a machine operating with a series of pile yarn carriers each having its own supply of differently colored yarns and wherein the supplies are moved one at a time to a tuft forming position. In this way each cross row of tufts can have any desired color arrangement independent of the other rows so that the finished product can have an almost limitless variation of pattern and color.

It is a further object of the invention to provide a machine of the type already mentioned wherein each carrier when arriving at the tuft forming position will have free tuft ends extending therefrom in such position as to permit the preforming of a row of tufts before the latter are applied to the backing fabric. After the row of tufts are preformed they are cut from their supply and are then pushed into the backing fabric.

It is a still further object of the invention to provide a machine of the type mentioned wherein the operation of preforming of tufts is followed by a movement of the yarn carrier in tuft forming position such as will draw off enough yarn for the next row of tufts to be formed from the carrier. The previously mentioned cutting operation occurs after the pull off operation.

It is a further object of the invention to provide a tuft fabric making machine with yarn control means operating in two stages, the first stage effecting the aforesaid preforming and the second stage, occurring after the tuft cutting operation, inserting the bights of the tufts into the backing fabric. The first stage as shown herein is accomplished by a tuft former which passes into guide means and the second stage is effected by needles or the like slidably within the tuft former.

In order that the various carriers of the series may be placed in tuft forming position they are arranged on a chain or conveyor mechanism traversing a path close to the tuft forming position and it is a further object of the invention to coordinate the movements of the conveyor mechanism and the aforesaid control means so that the latter can cross the path traversed by the carriers while the latter are relatively stationary in order to form the tufts and then be withdrawn from the path to permit the next carrier to move into tuft forming position.

After the tufts are attached to the backing fabric they are still in the guide means where they might interfere with the next tuft forming operation. In order to clear the guide means of the tufts it is another object of the invention to effect relative movement between the last

2

formed row of tufts and the guide means. As shown herein this result is accomplished by rotating the guide means, preferably when the backing cloth is being advanced.

5 The backing fabric is fed around a nose bar which is so shaped as to place parts of the backing successively at a tuft forming station aligned with the tuft forming position of the free ends of the carrier being operated upon. It is the further object of the invention to form 10 this bar with recesses which register with the previously mentioned needles, the parts of the nose bar adjacent to the recesses supporting the backing to prevent distortion thereof when the cut tufts are pushed into the backing.

Each carrier of the series is provided with a spool on 15 which tuft forming yarns are wound, these yarns being of any desired color, and the yarns lead from the spool down through tubes and project as free ends beyond the tubes. These tubes are formed with side guides at their lower ends to prevent objectionable lateral displacement 20 of the free ends and it is a further object of the invention to provide the previously mentioned tuft forming means with slots to receive the yarn guides of the tubes.

In order that the invention may be clearly understood reference is made to the accompanying drawings which 25 illustrate by way of example the embodiment of the invention and in which:

Fig. 1 is a side elevation partly in section of a machine made according to the present invention, part of the structure being shown diagrammatically, and certain of the 30 parts being broken away,

Fig. 2 is an enlarged view similar to a part of Fig. 1, but showing the parts in a different position,

Fig. 3 is a detail horizontal section on line 3—3, Fig. 2, on an enlarged scale,

35 Fig. 4 is a vertical section on line 4—4, Fig. 3,

Fig. 5 is a fragmentary vertical section on line 5—5, Fig. 3, showing certain tufts already inserted into the backing cloth and indicating by full and dotted lines how the preformed tuft is pushed into the backing cloth,

40 Fig. 6 is a vertical section on line 6—6, Fig. 5, showing a part of the guides which assist in forming the tufts,

Fig. 7 is a vertical section on line 7—7, Fig. 2,

Fig. 8 is a rear elevation looking in the direction of arrow 8, Fig. 1, on an enlarged scale,

45 Fig. 9 is a rear view looking in the direction of arrow 9, Fig. 1, showing part of the main shaft of the machine and the cams thereon,

Fig. 10 is an enlarged vertical section on line 10—10, Fig. 1,

50 Fig. 11 is an enlarged vertical section on line 11—11, Fig. 10,

Fig. 12 is an enlarged view looking in the direction of arrow 12, Fig. 2, showing the tuft cutting mechanism in two positions,

55 Fig. 13 is a diagrammatic view showing an electric circuit for controlling the locking mechanism for the carrier system,

Fig. 14 is a view looking in the direction opposite to that of Fig. 1 showing a mechanism for rotating the tuft 60 guide means,

Figs. 15, 16 and 17 are diagrammatic views showing successive positions of the yarn guide means as it turns to clear itself of a row of tufts which has just been inserted into the backing cloth,

65 Fig. 18 shows diagrammatically a series of yarn carriers as an illustration of one way in which the yarns on the carriers can be arranged to produce a fancy pattern, and

70 Fig. 19 is a detail vertical section on line 19—19, Fig. 10.

The machine to be set forth in more detail hereinafter

includes several different mechanisms which are designated generally as follows:

A conveyor system A which includes chains and a series of tuft yarn carriers which are moved one at a time to tuft forming position; advancing mechanism B for the conveyor system; the backing cloth feed system E which supplies a preformed sheet of material into which the tufts are punched; yarn control mechanism F which preforms tufts from the free yarn ends of the carrier in tuft forming position and then pushes the preformed tufts into the backing cloth; positioning mechanism G for the control means F; tuft cutting mechanism H; and tuft yarn guide mechanism K which cooperates with the mechanism F to preform tufts and then moves to clear the tufts which have been pushed into the backing cloth. Certain of these means and mechanisms either extend across the machine, or are present on each side of the machine, but except as otherwise noted the following detailed description will be limited principally to structure at one or the other side in order to avoid duplication.

Referring to Fig. 1, the machine includes side plates 1 and 2 which are held together in any approved manner as by cross girts 3. Arranged at the front of the machine, the left-hand part thereof as viewed in Fig. 1, is the conveyor system A which includes a supporting structure designated generally at 4 having an upright 5 and a cross beam 6. Suspended from the beam 6 is a bearing member 7 for a pullover shaft 8, there being one of these bearings at each side of the machine. To the front of shaft 8 are other bearings 9 which support a shaft 10. The shaft 8 is provided at each end thereof with a sprocket wheel 11 and each sprocket wheel meshes with an endless conveyor chain 12 having double links 13 alternating with single links 14, see Fig. 10. The chains extend around guide rolls 15 on shaft 10 downwardly and under other guide rolls 18 on another shaft 19. The shafts 17 and 19 may be journaled in any approved manner and the chain will ordinarily be kept taut so as to respond to any movement of the sprocket wheels 11. The rear parts of the chains have vertical runs 21 as shown in Fig. 1. A catwalk 20 may be located at the front of the machine for the convenience of the machine operator, see Fig. 1.

Spaced along the chains are tuft yarn carriers generally indicated at 25 each of which may be made for instance as shown in Fig. 11. Each carrier comprises a lengthwise bar 26 to each end of which is secured a hanger 27 fastened at 28 to one of the double links 13, see Figs. 10 and 11. The hangers at each end of the bar 26 support for rotation a spool 29 on which is wound a series of pile yarns Y arranged side by side on the spool. The yarns pass downwardly through tubes 30 which are secured to the bar 26 and a brace 31 for stiffening the bar is secured to the latter and also to the tubes. The lower ends of the flat sides of each tube 30 extend downwardly therefrom to form two guides 32, one on each side of a yarn passing through the tube. The guides 32 prevent lateral displacement of the depending free ends 33 of the yarns in the tubes. The yarns Y may be of any desired color to provide the required pattern in the finished product and are wound on the several spools to meet the pattern demands. Spring pressed gudgeons 34 on the spools fit into the hangers to afford means for rotatably mounting the spools and permitting their removal.

The advancing mechanism B for the conveyor system includes a ratchet wheel 35 keyed at 36 to the shaft 8 and cooperating with a pawl 37 pivoted at 38 on a 2-part lever 39 rockable on hub 40 of the pawl, see Figs. 10 and 19. A spring 41 normally holds the pawl against the ratchet wheel. The front end of a connector rod 42 pivots on a stud 43 supported by lever 39 and the rear end of the rod is pivoted at 44 to a lever 45 rockable on a fixed pivot 46. Lever 45 is operated by a cam 47 secured to the main shaft 48 of the loom. This shaft

5 may be rotated in any approved manner and preferably turns at a uniform rate during operation of the machine. Cam 47 has an incline part 49 effective when turning in the direction of arrow a, Fig. 1, to rock lever 45 in a clockwise direction from the position shown in Fig. 1 in order to cause the pawl 37 to rock shaft 8 and sprocket wheel 11 to move the chain 12 linearly so that the right-hand vertical run 21 thereof as viewed in Fig. 1 will rise. Cam 47 also has a second incline 50 to give the chains 10 an additional motion. The rocking of lever 45 in a clockwise direction under action of cam 47 is in two steps the first of which, effected by incline 49, is much larger than the second and acts to move the next carrier of the series to a tuft forming position designated at C, Fig. 2. After certain operations to be described herein-15 after have taken place the incline 50 causes the tube frame to move up a short distance to a pull off position C1, Fig. 2, to pull off yarn for the next operation of the carrier. The cam 47 then rocks lever 45 back to place the pawl 37 in position for its next advancing operation with respect to the ratchet 35 and the sprocket wheels 11. For each complete rocking of the lever 45 the chain 20 will be moved linearly a distance equal to the distance between adjacent carriers 25.

25 The backing cloth feed system for the backing cloth to which the tufts are applied includes a cloth roll 55 on which the ground or backing cloth 56 is wound, the latter extending around guide rolls 57 and then forwardly to a positioning bar or beam 58 which extends across and is fixed to the sides of the machine. This bar is supported in position in the loom by stands 59 which are bolted at 60 to the machine frame and the bar has a downwardly and forwardly extending upper plate 61 and a downwardly and rearwardly extending lower plate 62. The cloth 56 extends forwardly along plate 61, then around nose 63 of the bar 58 and then downwardly and rearwardly along the plate 62 to a takeup roll 64 which may be driven intermittently in any approved manner. The roll 64 is stationary during the tuft forming operation as will be described and then upon completion of the tufting operation the roll 64 turns slightly to move the backing cloth 56 a sufficient distance to present a new area thereof to the nose at the tuft forming station S.

30 From the takeup roll 64 the tufted fabric goes over a guide roll 65 and thence to a cloth roll 66 which may be driven in any approved manner. The cloth 56 therefore unwinds in a step-by-step motion from the roll 55, passes forwardly in front of and in engagement with the bar 58 through the tufting station S, and thence rearwardly to the takeup roll 64 from which it is led to the winding-up roll 66.

35 The bar 58 is provided with a series of horizontally arranged recesses 70 located between webs or fins 71 which support the ground fabric 56 between the recesses at the tuft forming station S. The under side of plate 62 is provided with a series of shallow grooves 72 leading downwardly and rearwardly from the recesses 70 in the direction of travel of cloth 56 toward roll 64. As will be described, the tufts which have been inserted into the fabric 56 project into their respective recesses 70 and then as the tufted fabric moves rearwardly the tufts pass along the grooves 72 so that they may remain inserted in the cloth without being acted on by forces which might otherwise tend to push them back through the cloth.

40 The yarn control mechanism F is located in front of the bar 58 and is supported by an I beam 75 extending across the machine and secured to the end plates 1 and 2. At each end of the I beam there is a slide bearing support means 76 and since these means are both alike only one of them will be described, see Figs. 1, 2, 7 and 8.

45 The bearing means 76 includes a housing 77 having a top and bottom 78 and 79 respectively and a vertical side wall 80. Upper and lower sets 81 and 82 respectively of rollers are mounted for rotation on pins 83 fixed to the housing as shown for instance in Fig. 7. A slide mem-

ber 84 has top and bottom plates 85 and 86 respectively engaging the upper and lower sets of rollers and has a side wall 87 which supports pins 88 on which rotate upper and lower inner sets of rollers 89 and 90 respectively. Each wall 87 extends rearwardly at 91 and a lengthwise bar 92 fixed to the parts 91 extends across the machine. Secured in the bar 92 is a flat elongated tuft former 93 the rear edge of which is formed with teeth 94 separated by vertical transverse slots 95. The teeth 94, the tuft former 93, the bar 92, the parts 91 and the walls 87 and 89 and 90 thereon are therefore a unit slideable back and forth on the sets of rollers 81 and 82. Each wall 87 has a forwardly extending arm 96 pivoted at 97 to a lever 98.

Between rollers 89 and 90, see Fig. 7, is an end slide plate 99 the rear end of which connects with a push bar 100 extending across the machine and moving with each slide plate 99. Secured in push bar 100 and extending rearwardly therefrom is a set of needles 101 which are blunt on their rear ends as shown in Fig. 5 and are slideable in holes or bores 102 in the tuft former 93. These holes pass through the teeth 94 as shown in Fig. 3. The front end of each end slide plate 99 is pivoted at 103 to a lever 104. Levers 98 and 104 are pivoted at 105 on bearing arms 106 secured at 107 to I beam 75.

The rear end of each tooth 94 is formed with a rounded cavity 108 adapted to receive a tuft yarn, and grooves 109 extend forwardly from the cavities in both the top and bottom faces of the teeth.

The positioning means G for the tuft control means F includes the two levers 98 and 104 and their respective cams 110 and 111 secured to shaft 48. These cams operate cam levers 112 and 113 connected by rods 114 to levers 98 and 104 respectively. Cams 110 and 111 are very similar throughout the greater part of their contours so that the tuft former 93 and needles 101 move together for the greater part of their horizontal sliding motion. When the tuft former 93 and needles 101 are in the position shown in Fig. 2, however, the tuft former 93 comes to rest and shortly thereafter the needle push bar 100 has an additional rearward motion.

The tuft cutter mechanism H includes a thin cutter blade 115 which is secured to a horizontal bar 116 each end of which is secured to a collar 117 fastened to a transverse reciprocable horizontal rod 118. One end of this rod and the associated parts are shown in Fig. 12. The bar 118 has each end thereof mounted for endwise sliding in a bearing 119 fixed with respect to the machine, only one of these bearings being shown in Fig. 12.

Secured to the main shaft 48 is a cam 120 having a cam groove 121 which receives a roller 122 on the lower end of a lever 123 pivoted on a stud 124 held stationary with respect to the machine by a stand 125 secured to the machine, see Figs. 1 and 9. The upper end of this lever 123 has a roll 126 which fits into a groove 127 in the collar 117. When the cam 120 oscillates the lever 123 the cutter blade will be moved from the full line position to the dotted line position shown in Fig. 12 and then back to the full line position. The time and cycle of operation for action of the cutter will be described more fully hereinafter.

The tuft guide mechanism K extends across the machine and includes upper and lower guide bars 130 and 131 respectively between which extend a number of thin vertical webs or spacers 132 which define between them guide channels 133 to receive the teeth 94 of the yarn control means. The slots 95 between the teeth receive the webs as indicated in Fig. 3. The two bars 130 and 131 have their outer surfaces 135 arcuate about a longitudinal axis which is central with respect to the two bars. A support stand 136 extending across the machine has secured thereto a center bearing 137 having an upper concave surface 138 to fit the curved surface 135 of whichever of the two bars 130 and 131 is in low position, see Fig. 5.

The bars 130 and 131 are joined at their ends by cross heads one of which is shown at 140 in Fig. 6. Each cross head has a gudgeon 141 rotatable in a fixed bearing 142, one of the gudgeons and bearings being shown in Fig. 6. The axis of the gudgeons is the same as that of the curved surfaces 135.

Fixed to one of the gudgeons 141, see Fig. 14, is a gear pinion 145 and a holding wheel 146 having recesses 147 on opposite sides thereof to receive a resiliently mounted holding roll 148. When the roll 148 is in one or the other of the notches 147 the bars 130 and 131 will be disposed with their channels 133 horizontal and in position to receive the teeth 94.

A gear wheel 150 of twice the size of gear pinion 145 meshes with the latter and is mounted on a shaft 151 supported by the machine frame. Fixed with respect to the gear 150 is a ratchet wheel 152 which in the present instance has four teeth 153 to receive a pawl 154 pivoted at 155 on a lever 156 rocking about the shaft 151. Lever 156 is connected by rod 157 to a lever 158 movable about a fixed stud 159 and having the free end thereof positioned by cam 160 fixed to the shaft 48. The parts just described are so proportioned that an incline 161 on the cam 160 will cause the pawl 154 to give the ratchet wheel 152 and the gear 150 a one-quarter rotation in the direction of arrow b, Fig. 14, for each rotation of the shaft 48, resulting in a one-half rotation of the gear pinion 145 and the bars 130—131 through the successive positions shown in Figs. 15-17. After this rotation has been completed the holding roll 148 will keep the bars 130—131 in the position to which they have been moved as the pawl 154 has its return motion.

Fig. 10 shows one end of the shaft 8 and associated parts including a bearing member 175, additional to bearing 7, held in fixed position on the machine and having a magnetic disc 176 secured thereto in fixed position. An electromagnetic brake coil 177 close to disc 176 is secured to and rotates with shaft 8 by reason of parts 178 and 179, as shown in Fig. 10. During rotation of the shaft 8 as already described the coil is deenergized but as soon as its angular movement is completed the coil becomes energized to prevent further accidental turning of the shaft.

A circuit for energizing the coil 177 is shown diagrammatically in Fig. 13 and includes a switch 180 opened and closed by a cam 181 which makes a rotation for each tuft forming operation of the machine. This cam has two high areas 182 and 183 which when under the switch open the latter to deenergize the brake during rotation of the shaft 8. When the high areas pass beyond control of the switch the latter close and the coil 177 then becomes energized from a source of electric power designated generally at 185. The brake mechanism of itself forms no part of the present invention other than providing means for locking shaft 8 when it is intended to be at rest and any other form of brake can be employed. The electromagnetic brake is deenergized whenever lever 45 moves to advance the carrier system.

Preparatory to operation of the machine the ground cloth 56 will be placed in the machine and extended around the bar 58 and then connected to the takeup roll roll 64. The various spools of the different carriers in the conveyor chain will also have been wound to produce the desired pattern. In Fig. 18 four carriers I, II, III, IV are shown with four different kinds of yarns indicated, although it is to be understood that the color of yarns can be selected in any variety desired. In Fig. 18 the four yarns are indicated by heavy and light solid lines and heavy and light dotted lines, the yarns being arranged on their spools so that when they are moved successively to tuft forming position they will produce the desired pattern. The spools are then connected to the hangers of the various carriers in their correct order. Although only four yarn carriers are shown in Fig. 18 it is to be under-

stood that any desired number may be used depending upon the kind of pattern to be produced.

With all of the carriers provided with spools and with the ground cloth 56 in place the operation of the machine may be assumed to begin with a carrier in the position shown in Fig. 1 and with the tuft yarn control mechanism F retracted in forward position and a given crosswise area of the fabric 56 at the tufting station. The free ends will hang down from the carrier and be aligned by the depending sides 32 of the tubes on the carrier. The cams 112 and 113 will then move the tuft former and also the needles rearwardly to the position shown in Fig. 2, the slots 95 receiving the guides 32 and the teeth 94 on the tuft former engaging their respective free ends and pushing them through the guide channels 133 to preform the free ends into tufts and push them against those parts of the ground cloth 56 opposite the recesses 70. As the teeth 94 pass into the channels 133 cavities 108 will receive the free ends of the yarn and hold them in position for the preforming operation, and the sides of the tufts will enter grooves 109. The tuft lever 45 will then be rocked a slight amount by cam 47 to lift the carrier a short distance sufficiently to pull off enough yarn from its spool for the next tuft forming operation of the carrier. When the teeth are fully in position as shown in full lines in Fig. 5 there is enough friction exerted against the preformed tuft to cause rotation of the spool when the corresponding carrier is given its pull-off motion. It is found that the free ends, although drawn across the edge of the cutter blade, will not only not be cut by the blade but will be held by it during the pull off operation. During the time the advancing mechanism is moving the conveyor system one of the high points 182-183 will open the switch 180 to deenergize the holding coil 177. As soon as the conveyor system has moved sufficiently to pull off the proper amount of yarn the switch 180 will again close to energize coil 177 to hold the shaft 8 against accidental turning. Cam 120 then acts on lever 123 to move the rod 118 longitudinally to draw the lower sharpened edge of the blade 115 across the tuft yarns to cut them from their spool.

Cam 111 then acts to rock lever 104 to move the needles 101 rearwardly through the teeth 94 and against the bights of their respective preformed tufts and push the bights from the full line position, Fig. 5, through the ground cloth 56 partway into the recesses 70 to the dotted line position, Fig. 5. Cam 111 then retracts the needles to their normal position with respect to the teeth 94, after which both cams 110 and 111 rock their levers 94 and 104 respectively to move the tuft former and needle structure forwardly out of the path traversed by the carriers. The switch 180 is again opened and cam 47 operating through lever 45 and the structure shown in Fig. 19 advances the chain system until the next carrier, the one below the carrier previously in tufting position, has been lifted to a position where its free ends are placed for the next tuft forming operation. The switch 180 then closes.

As soon as the teeth 94 have been fully withdrawn from between the bars 130 and 131 the cam point 161, see Fig. 14, will cause rotation of the guide bars from the position shown in Fig. 14 through the successive positions shown diagrammatically in Figs. 15-17 and will continue the rotation until the bars have been given a one-half turn. This turning of the bars results in clearing them and channels 133 of the row of tufts previously in the channels, and the latter will be ready for the next tuft forming operation.

During the turning of the bars 130 and 131 the takeup roll 64 will move the fabric 56 so that the previously formed row of tufts will move downwardly in the same direction in which the adjacent parts of the bars 130 or 131 move, and these two movements, occurring together, insure further removal of the tufts from the channels 133. A fresh area of the backing cloth 56 is now at the tuft forming station and the operation can be repeated.

As the tufted part of the ground fabric 56 moves away from the tuft forming station the bights of the tufts T will move along the grooves 72 and will therefore not be acted on by any force tending to push them back through the backing cloth 56. The fabric when taken from the cloth roll 66 can have the back thereof treated with any convenient or appropriate form of adhesive which will secure the bights of the tufts to the backing fabric to hold the tufts firmly in position.

From the foregoing it will be seen that the invention sets forth a machine wherein tuft fabrics of the punched type can be made with practically unlimited pattern designs. Any pattern which it is desired to reproduce can be determined by the order in which the yarns are arranged on the spools according to their color or other characteristic, and as many carriers can be provided as are necessary for repeat of the pattern. The free ends of yarn extending from the carrier in tuft forming position are first preformed into tufts by cooperation of the tuft forming means and the guide mechanism K, after which the tufts are cut from their spool and then pushed into the backing cloth by the needles. During the pulling off operation the free ends may be held partly by frictional engagement between their bights and the backing cloth as established by the rear ends of the teeth 94 and to some extent frictional engagement of the sides of the tufts by the bars 130 and 131. Also, it is found that the edge of the knife along which the tuft ends extend toward their spool not only does not cut the yarns but assists in holding them against retrograde movement during the pulling off operation. The tuft forming mechanism is moved between adjacent carriers for its tuft forming operation and then is moved out of the path traversed by the carriers to permit the next carrier to move into tuft forming position. Any convenient form of backing, such as a Latex compound, can be used to secure the bights of the tufts to the backing cloth 56. The invention also sets forth an improved method which includes the preliminary steps of winding the spools according to the desired pattern and then after the spools have been applied to the chains acting on the free ends to form tufts which are inserted into the backing cloth subsequent to the cutting operation.

Having now particularly described and ascertained the nature of the invention and in what manner the same is to be performed, what is claimed is:

1. In a machine for applying pile tufts to a backing fabric which moves to place parts thereof successively at a tuft forming station during operation of the machine, a series of carriers each provided with a supply of tuft pile yarns having free ends, advancing means operating intermittently to move the carriers along a path to locate them in a given order and one at a time in tuft forming position for an interval of time, control means for said free ends normally out of said path, positioning means to move the control means across said path during one of said intervals and cause the control means to move the free ends of the carrier in said tuft forming position to positions adjacent to the ground fabric, the advancing means being thereupon effective to move the carrier in tuft forming position to pull off pile yarn, cutter means thereupon effective to cut said free ends from said carrier, the positioning means thereupon causing the control means to push the cut off free ends through that part of the ground fabric at said station, said positioning means thereupon moving the control means out of said path, and the advancing means thereupon moving the carriers along said path to locate the next carrier in said series in said tuft forming position while said control means is out of said path preparatory to another tuft forming operation of the machine.

2. The machine set forth in claim 1 wherein the carriers are mounted on endless chains and the advancing means is operatively connected to the chains.

3. The machine set forth in claim 1 wherein the carriers are mounted on chains operatively connected to the

advancing means and a carrier in tuft forming position is supported by vertical runs of the chains and the free ends depend from the carrier and the control means moves horizontally.

4. In a machine for applying pile tufts to a backing fabric at a tuft forming station, feed means operative to move portions of said backing fabric successively to said station, a series of carriers each provided with a supply of tuft pile yarns having free ends, advancing means operating intermittently to locate the carriers in a given order and one at a time to a tuft forming position with the free ends thereof adjacent to said station, control means to act in two stages on the free ends adjacent to said station, said control means effective during the first stage to move said free ends adjacent to the backing fabric, the advancing means thereupon moving the carrier in tuft forming position with respect to the control means to pull off pile yarn, cutter means thereafter effective to cut the free ends from said carrier, said control means thereupon being effective during the second of said stages to insert the cut off free ends into that part of the ground fabric at said station, and the advancing means thereupon moving said carrier away from said tuft forming position and moving the next carrier in said series to said tuft forming position and the feed means moving another portion of the backing fabric to said station.

5. The machine set forth in claim 4 wherein the tuft pile yarns of each carrier are independent of the tuft pile yarns of the other carriers.

6. The machine set forth in claim 4 wherein the control means during said first stage holds the free ends against the ground fabric while the advancing means moves the carrier to pull off the pile yarn.

7. The machine set forth in claim 4 wherein the control means includes a set of teeth, one for each free end, to move the free ends against the ground fabric during said first stage and includes also a set of needles, one for each free end, movable from within the teeth to push the free ends into the ground fabric during said second stage.

8. The machine set forth in claim 4 wherein the cutter means includes a blade parallel to the carrier in tuft forming position and mechanism operative after the advancing means has pulled off pile yarn to move the blade laterally across all of the free ends to sever them from the carrier.

9. The machine set forth in claim 8 wherein the blade is stationary and the pile yarns extend across and in engagement with the blade when the advancing means is pulling off pile yarn and the blade cooperates with the control means to hold the pile yarn during the pull-off operation of the advancing means.

10. The machine set forth in claim 4 wherein the machine has spaced guides and the control means during said first stage moves the free ends between said guides to preform tufts in said free ends prior to movement of the advancing means to pull off pile yarn.

11. The machine set forth in claim 10 wherein the guides and control means cooperate to hold the free ends frictionally during the pulling off of pile yarn by the advancing means.

12. The machine set forth in claim 10 wherein the control means during the second stage pushes the preformed tufts into the ground fabric.

13. The machine set forth in claim 10 wherein the cutter means is between said guides and the carrier in tuft forming position and the control means cooperates with the guides to hold the tufts during operation of the cutter means.

14. The machine set forth in claim 4 wherein the control means includes a set of teeth, one for each free end, to move the free ends against the ground fabric during said first stage and includes also a set of needles, one for each free end, movable to push the free ends into the backing fabric during said second stage.

15. The machine set forth in claim 14 wherein the 75

machine has a support beam for the ground fabric having recesses aligned with said needles and fins on the beam adjacent to the recesses support the backing fabric during the second stage of operation of the control means.

5 16. The machine set forth in claim 4 wherein the control means includes a set of teeth, one for each free end, which engage and move the free ends against the ground fabric during said first stage.

10 17. The machine set forth in claim 4 wherein the control means includes a set of teeth, one tooth for each free end, and the carrier in tuft forming position includes a set of tubes, one for each free end, each tube having a part thereof in guiding position relative to the associated yarn and the teeth are separated by slots which receive said parts of the tube during the first stage of operation of said control means.

15 18. In a machine for applying pile tufts to a ground fabric, a carrier provided with a supply of tuft pile yarns having free ends, means effective to preform tufts in said free ends while the latter are attached to said supply, means thereafter effective to cut the preformed tufts from said supply, and mechanism thereafter effective to insert said cut preformed tufts into said ground fabric.

20 19. In a machine for applying pile tufts to a ground fabric, a carrier provided with a supply of tuft pile yarns having free ends, means to effect holding of the free ends while the latter are attached to said supply, means thereafter effective to cut the free ends from said supply, and means effective thereafter to push the cut free ends 25 in a direction from the holding means toward and into the ground fabric.

25 20. In a pile tuft yarn control means for a machine having backing cloth and free yarn ends to be incorporated into the backing cloth, support means for attachment to the machine, an elongated member having a set 30 of transverse teeth, one tooth for each free end, mounted for movement on the support means in the direction of the length of the teeth, and a set of needles, one needle for each tooth, each needle deriving support from its tooth and slidably relatively to and guided by its tooth 35 in said direction.

21. The control means set forth in claim 20 wherein the needles are slidable within the teeth.

22. A machine operating with the yarn control means 40 set forth in claim 20 wherein two operating mechanisms are provided, one for each of said sets, said operating mechanisms causing the sets to move in unison toward the backing cloth during part of the operation of the machine and the mechanism corresponding to the teeth holding the latter stationary and the mechanism corresponding to the needles causing the latter to move relatively to the teeth into the backing cloth during another part of the operation of the machine.

23. The machine set forth in claim 22 wherein the operating mechanisms include two cams, one cam for each mechanism, fixed to a shaft which rotates during operation of the machine and wherein the contours of said cams are substantially the same for controlling said mechanisms during the first named part of said operation of the machine and wherein the contour of the cam for the mechanism corresponding to the set of needles differs from the contour of the other cam to cause said set of needles to move relatively to the teeth.

24. In a pile yarn control means for a machine having 45 backing cloth and free yarn ends to be incorporated into the backing cloth, supporting means on the machine, tuft forming means including a set of teeth, one tooth for each free end, mounted for sliding movement on said support, and other means supporting a set of needles, 50 one needle for each tooth, slidably within and guided by said tuft forming means for movement relatively to the latter, said tuft forming means by guiding said other means maintaining the needles in alignment with their respective teeth.

25. In yarn control and guide means for a machine

having a backing cloth and a row of free ends of pile yarn, guide means located between said free ends and the cloth, tuft forming means effective to push said free ends into said guide means to preform tufts in said free ends and thereafter attach said tufts to said backing cloth, means to move said tuft forming means away from said guide means, the tufts remaining in said guide means, and means thereafter effecting relative movement between said guide means and the backing cloth to effect removal of the tufts from the guide means.

26. The structure set forth in claim 25 wherein the guide means is formed with a channel for each tuft and the tuft forming means has a tooth to enter each channel and cooperate with the guide means to preform the tufts.

27. The structure set forth in claim 25 wherein the guide means includes two spaced bars between which the tuft forming means moves when preforming the tufts, and wherein means are provided to rotate said bars to effect removal of the tufts from between said bars.

28. The structure set forth in claim 25 wherein said guide means includes two spaced bars connected by a plurality of webs which define a plurality of channels between the bars and wherein the tuft forming means has a tooth to enter each channel to preform the tufts and wherein means are provided to give said guide means a one-half rotation after the tuft forming means has moved away from the guide means to effect removal of the tufts from the channels.

29. The structure set forth in claim 25 wherein the backing cloth moves progressively in a given direction to move a row of tufts attached thereto away from a tuft forming station and wherein the guide means includes two spaced bars between which the row of tufts extends and wherein means are provided to turn said bars in such manner that the parts of the bars adjacent to said cloth move in the same direction as the cloth moves when moving the row of tufts away from said station.

30. The structure set forth in claim 25 wherein the tuft forming means moves in a straight line toward and from the backing cloth incident to preforming the tufts and wherein means are provided to rotate said guide means to effect disengagement with the row of tufts an angular distance equal to at least a one-half rotation thereof.

31. In a machine for applying pile tufts to a backing fabric at a tuft forming station, a feed system advancing a backing cloth at regular intervals, a guide beam across which the backing cloth moves toward and from said station, said beam having an upper plate inclined downwardly and forwardly toward said station and having a lower plate inclined downwardly and rearwardly from said station and having a rounded nose joining said plates, a plurality of spaced recesses in said nose arranged horizontally along said station across which the cloth extends, the beam having cloth supporting parts between said recesses, and mechanism comprising a plurality of needles aligned with the recesses effective to push pile

tufts into those parts of the cloth aligned with the recesses and into the recesses between said cloth supporting parts of the beam.

32. The machine set forth in claim 31 wherein the beam is provided with grooves aligned with said recesses extending in the direction of travel of the cloth to receive those parts of the tufts which have been inserted into the backing cloth as the latter moves with respect to the beam.

33. In a yarn carrier for a tuft forming machine wherein tufts are applied to a backing cloth by a set of teeth movable in a direction toward the cloth, a lengthwise bar, a spool having a plurality of yarns wound thereon rotatably mounted on the bar, yarn tubes secured to the bar extending transversely with respect thereto and from which free ends of the yarns extend, said yarn tubes having the ends thereof remote from the spool formed with lateral guides substantially parallel to said direction of movement of the teeth to hold said free ends in position for engagement by said teeth.

34. In a machine for applying pile tufts to a cloth backing, a pair of transporting chains movable in unison, a plurality of yarn carriers remaining connected to said chains at spaced intervals therealong during operation of the machine, said carriers having free yarn ends extending therefrom, yarn control means movable between two adjacent carriers on said chains to insert the free ends of one of said two carriers into the backing cloth.

35. A machine set forth in claim 34 wherein said yarn control means after inserting the free ends into the backing cloth moves out of a position between said two carriers and advancing means thereafter moves the chain to present another yarn carrier in position for its free ends to be attached to the backing cloth by the yarn control means.

36. The method of attaching pile tufts to a backing cloth in such manner as to produce a tufted pattern, said method including the following steps: winding a plurality of spools with yarns arranged thereon with respect to each other in an order corresponding to the pattern, drawing off the yarns of each spool to form a row of free yarn ends, moving said spools successively to present said rows of ends one at a time in a tuft forming position, thereafter cutting said row of free ends in said position from the corresponding spools, and thereafter inserting the cut row of free ends into the backing cloth.

37. The method set forth in claim 36 wherein the free ends are preformed into tufts before being cut from the spools.
